DISPOSABLE SAFETY RAZOR

John P. Loughlin, Shenandoah, Pa.

Application April 12, 1957, Serial No. 652,536

1 Claim. (Cl. 30—32)

The present invention relates to new and useful improvements in safety razors and has for its primary object to provide, in a manner as hereinafter set forth, an inexpensive article of this character which, if desired, may be discarded after a single use.

Another very important object of the invention is to provide an improved disposable safety razor of the character described wherein the parts are permanently assembled, thus preventing insertion of a new blade.

Other objects of the invention are to provide a safety razor of the character described which will be of relatively simple construction, sanitary, of light weight and which may be manufactured at low cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is an elevational view of a disposable safety razor embodying the present invention;

Figure 2 is a perspective view of the invention, showing the parts separated;

Figure 3 is a sectional view taken substantially on the line 3—3 of Figure 1;

Figure 4 is a sectional view through the head assembly, taken substantially on the line 4—4 of Figure 3;

Figure 5 is a sectional view taken substantially on the line 5—5 of Figure 3; and

Figure 6 is a fragmentary view in vertical section through one end portion of the head assembly, showing the method of engaging the handle hooks with the blade retaining plate.

Referring now to the drawing in detail, it will be seen that the embodiment of the invention which has been illustrated comprises a handle which is designated generally by reference numeral 7. Permanently mounted on the handle 7 is a head assembly 8.

The head assembly 8 comprises a transversely elongated lower plate or guard 9 which is preferably of a suitable plastic. Mounted on the guard 9 is a double edged blade 10. Mounted on the blade 10 is a retaining plate 11 for said blade, which plate 11 is also preferably of a suitable plastic.

As shown to advantage in Figure 2 of the drawing, the guard 9 has formed in its central portion a longitudinally extending slot 12. Adjacent the ends of the longitudinal slot 12, the guard 9 is further provided with transverse slots or elongated openings 13. Adjacent to and paralleling the cutting edges 14 of the blade 10, the guard 9 further includes slots 15 for the passage of lather, etc., from said blade.

The blade 10 is provided in its central portion with a longitudinal slot 16 which is in registry with the slot 12 in the guard 9. Adjacent the ends of the slot 16, the blade 10 still further includes a pair of transverse slots or elongated openings 17 which are aligned with the openings or slots 13.

The clamping or retaining cap or plate 11 is substantially crescent-shaped in cross-section and has formed integrally therewith on its concave side a longitudinal rib 18 which is engaged in the aligned slots 16 and 12. The clamping plate or cap 11 further includes, adjacent the

2

ends of the rib 18, a pair of flat ears or lugs 19 which project through the aligned openings 17 and 13 in the blade 10 and the guide 9. The ears or lugs 19 have formed therein substantially rectangular openings 20. As shown to advantage in Figure 6 of the drawing, the openings 20 include bevelled rear walls 21.

The handle 7, which is of a suitable resilient plastic, is substantially U-shaped, said handle including a bight portion 22, legs 23 comprising inwardly bowed portions 24, said legs terminating at their free ends in inturned hooks 25 of rectangular cross-section which are engageable in the openings 20 in the ears or lugs 19. The hooks 25 terminate in bevelled free ends 26 adapted to ride on the bevelled surfaces or walls 21 of the openings 20 to facilitate engaging said hooks with a snap action for permanently anchoring said hooks in the ears or lugs 19.

It is thought that the invention will be readily understood from a consideration of the foregoing. Briefly, to assemble the razor the blade 10 is positioned on the guard 9 and the blade retaining plate or cap 11 is mounted on said blade 10 with the rib 18 engaged in the slots 16 and 15 and the ears or lugs 19 projecting through the registering openings 17 and 13. The legs 23 of the handle 7 are then spread and the hooks 25 are seated in the openings 20, as shown in Figure 6 of the drawing.

The legs 23 of the resilient handle 7 are then compressed or forced together for snapping the hooks 25 through the ears or lugs 19 in an obvious manner, this operation being facilitated by the bevelled free ends 26 of said hooks riding on the complementary walls 21 of the ear or lug openings 20. When thus pressed in the ears or lugs 19 (see Figure 3) the hooks 25 cannot be withdrawn, thereby preventing the razor from being disassembled.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

A safety razor comprising: a head including a guard and a plate for the reception of a blade therebetween, ears on the plate projecting through the guard, said ears having transverse polygonal apertures therein comprising inwardly and forwardly bevelled rear walls, a generally U-shaped, resilient handle mounted on the head astraddle the ears, and inturned polygonal hooks on the ends of said handle insertable under pressure through the apertures from the outer ends thereof for snapping behind the ears and anchoring the hooks therein for securing the guard and the plate together, said hooks including bevelled free ends slidable on the bevelled aperture walls and cooperable therewith for facilitating the insertion of said hooks in said ears.
